W. C. H. NOBLE,
OIL BURNING APPARATUS,
APPLICATION FILED JUNE 17, 1911.

1,029,818.

Patented June 18, 1912.

UNITED STATES PATENT OFFICE.

WILLIAM C. H. NOBLE, OF LOS ANGELES, CALIFORNIA.

OIL-BURNING APPARATUS.

1,029,818.

Specification of Letters Patent. Patented June 18, 1912.

Application filed June 17, 1911. Serial No. 633,842.

To all whom it may concern:

Be it known that I, WILLIAM C. H. NOBLE, a citizen of the United States, residing at Los Angeles, in the county of Los Angeles and State of California, have invented a new and useful Oil-Burning Apparatus, of which the following is a specification.

This invention relates to oil burners of the "outside mixing" type, and the main object of the invention is to provide in a burner of this type, means for forcibly breaking up the oil and mixing the oil with the air.

15 A further object of the invention is to provide a burner of this type which is adapted for use with crude or heavy oils.

Other objects of the invention will appear hereinafter.

20 The accompanying drawings illustrate the invention, and referring thereto—Figure 1 is an elevation of the apparatus. Fig. 2 is a plan of the burner, partly in section on line x^2-x^2 Fig. 3. Fig. 3 is a vertical section on line x^3-x^3 Fig. 2. Fig. 4 is a horizontal section on line x^4-x^4 Fig. 3. Fig. 5 is a section on line x^5-x^5 in Fig. 2.

The burner comprises a casing 1 adapted to serve as an air chamber and as a support 30 for the burner parts, said casing having an upwardly converging or conical upper portion 2, said upper portion being provided at its upward end with an outward flaring flange 3. A top member 4 extends over the 35 opening within the annular flange 3 and supported on said flange by arms 5 extending outwardly and downwardly from the top member 4 and secured at their lower ends by means of bolts 6. The top member 40 4 may be formed as a disk having a down turned outwardly flaring flange 7 at its rim the flanges 3 and 7 approaching one another and forming a converging annular outlet or opening 9 for the air and oil, the 45 air and oil being mixed directly at and adjacent to this outlet.

An oil chamber 10 is formed or provided on the bottom of the casing 1, and an oil supply tube 11 communicates with said 50 chamber 10. Mounted centrally within the casing 1 and chamber 10 is a vertical spindle or shaft 12 supported by a ball bearing 13 on the casing 1 and extending downwardly through the chamber 10 said shaft 55 being connected at its lower end to suitable driving means hereinafter set forth, where-

by it is rotated at high velocity. A channel or passage 14 is formed in said shaft 12 and communicates by lateral channels 15 with the interior of oil chamber 10, said channel 14 being closed at its upper end by a screw plug 16. A fan-wheel is provided on said shaft said fan-wheel comprising a hub portion 19 keyed on the shaft as indicated at 20, a rim portion 21 connected to 60 said hub by arms 22 and blades 23 and 24 carried by said rim portion. Channels or passages 25 extend from the central channel 26 formed in the hub 19 to an annular channel 27 formed in the peripheral portion 70 of the rim 21. An annular slot 27' is formed in said rim portion extending outwardly from the annular channel 27 and forming the oil outlet, said outlet facing the annular opening 9 aforesaid. The blades 23 and 24 75 on the fan-wheel are shaped and placed in such a manner as to drive the air outwardly in the rotation of the fan-wheel, and the lower blades 23 are preferably arranged at somewhat greater radius than the upper 80 blades 24, so that the current of air supplied by the lower blades 23 moves at a somewhat higher velocity than the upper current of air. The arms 22 of the fan-wheel are preferably inclined as shown in 85 Fig. 5, to enable them to act as fan blades, forcing the air to the upper blades of the fan-wheel.

The burner above described may be 90 closed in the combustion chamber of a furnace, one of the walls of such chamber being indicated at 28, said wall having a door 28' for admission of air. Air may be supplied to the air chamber or casing 1, through a pipe 30 connected with the outlet of the 95 blower 31, whose shaft 32 is operated by any suitable motor such as electric motor 33. Said shaft 32 may also be connected by any suitable means such as a flexible shafting 34, to the vertical shaft 12 aforesaid. By 100 means of the blower 31, air is supplied to the casing 1, at sufficient pressure to enable it to be delivered to, and received by the fan blades 23 and 24 at a density such as to enable efficient operation of the blades and to 105 cause the air to be delivered at the outlet 9, in a more or less compressed condition, the expansion of this compressed air causing more rapid issue of the air from the burner. In order that the oil may be supplied to this 110 jet of compressed air, it is desirable that the oil should be furnished to the oil distrib-

uting channels at a pressure equal to, or above the pressure of the air. For this purpose the oil supply tank 36 which is connected to the oil pipe 11 aforesaid, may be provided with means for producing pressure therein, said means consisting for example, of a pipe 37 connected to the outlet of a positive blower 38 operated for example, by a gear 39 from the shaft 32 aforesaid.

The operation is as follows: The motor 33 being set in operation, operates the blower 31, forcing air under moderate pressure into the casing or air chamber 1. At the same time the operation of the shaft 32 by the motor working through the flexible shaft 34, rotates the spindle 12 at high velocity causing the blades 23 and 24 to force the air outwardly from the upper end of the chamber 1 through the annular outlet 9, the air passing upwardly between the arms 22 of the fan-wheel so as to reach the upper blades. The current of air from the lower blades 23 on striking the upwardly flaring flange 3 is deflected upwardly against the upper current of air upon the blades 24, said upper current of air being deflected downwardly by the rim flange 7 so as to impinge on the lower current of air. The rotation of the shaft 12 also causes the oil which has been forced into chamber 10 to be driven outwardly through channels 25 to the annular channel 27, whence it passes in a sheet through the annular outlet 27', this sheet of oil moving at high velocity and entering between the lower and upper currents of air aforesaid, is immediately atomized and mixed with the air, the mixture being formed directly at and adjacent to the outlet 9 and being immediately thereafter burned, so that the principle of combustion is that of an outside mixing burner.

What I claim is:

1. In an oil burning apparatus, the combination of a casing having a top member with a downwardly flaring flange and the side of said casing having an upwardly flaring flange said flanges being separated to form an annular outlet, a shaft mounted to rotate in said casing, a fan-wheel carried by said shaft and provided with passages hav-

ing outlets opening at the periphery of the fan wheel, blades on said fan wheel above and below said openings of the oil passages for forcing air against the upper and lower flanges aforesaid, means for supplying oil to said passages in the fan-wheel, and means for rotating said shaft.

2. In an oil burning apparatus, the combination of a casing having a top member with a downwardly flaring flange and the side of said casing having an upwardly flaring flange said flanges being separated to form an annular outlet, a shaft mounted to rotate in said casing, a fan-wheel carried by said shaft and comprising a rim portion, arms connecting said rim portion to said shaft, said arms and rim portion being provided with passages having outlets facing the said annular outlet of the casing, blades on said fan-wheel above and below said rim for forcing air against the upper and lower flanges aforesaid, means for supplying oil to said passages in the fan-wheel, and means for rotating said shaft.

3. In an oil burning apparatus, the combination of a casing having a top member with a downwardly flaring flange and the side of said casing having an upwardly flaring flange said flanges being separated to form an annular outlet, a shaft mounted to rotate in said casing, a fan-wheel carried by said shaft and comprising a rim portion, arms connecting said rim portion to said shaft, said arms and rim portion being provided with passages having outlets facing the said annular outlet of the casing, blades on said fan-wheel above and below said rim for forcing air against the upper and lower flanges aforesaid, means for supplying oil to said passages in the fan-wheel, and means for rotating said shaft, the lower blades of said fan-wheel being at a greater distance from the center of rotation than the upper blades.

In testimony whereof, I have hereunto set my hand at Los Angeles, California, this 9th day of June 1911.

WILLIAM C. H. NOBLE.

In presence of—

ARTHUR P. KNIGHT,
GLADYS RUSSELL.
